STEAMING SPOOL

Frederick R. Reutter, Waterbury, Conn., assignor
to Scovill Manufacturing Company, Water-
bury, Conn., a corporation of Connecticut

Application November 11, 1933, Serial No. 697,605

6 Claims. (Cl. 242—123)

This invention relates to spools, and more particularly to a sheet metal spool adapted for use in the steaming and soaking of spooled material in the manufacture of textiles such as silk.

- 5 8 One object of this invention is to provide a metal spool of the above nature having a pair of concentric tubes supported at their ends in a pair of circular discs, the outer tube being reinforced against crushing stresses.
- 10 10 A further object is to provide a spool of the above nature which will be simple and strong in construction, have a minimum number of parts, be inexpensive to manufacture, compact, ornamental in appearance, and very efficient and durable in use.

15 With these and other objects in view, there has been illustrated on the accompanying drawing, one form in which the invention may be conveniently embodied in practice.

20 In the drawing:

Fig. 1 represents a side elevational view of a winding spool embodying the invention.

Fig. 2 is an end view of the same.

Fig. 3 is a longitudinal sectional view on a 25 slightly enlarged scale, the view being taken along the broken line 3—3 of Fig. 2, looking in the direction of the arrows.

Fig. 4 is a transverse sectional view taken along the line 4—4 of Fig. 3, looking in the direction 30 of the arrows.

Referring now to the drawing in which like reference numerals denote corresponding parts throughout the several views, the numeral 10 generally indicates a metal winding spool embodying the invention, said spool consisting of an outer cylindrical shell or barrel 11, a pair of transverse end discs 12 and 13, and an inner concentric tubular hub 14. The shell 11 and hub 14 are preferably each formed of 35 single strips of stainless steel. The inner hub 14 has its longitudinal side edges abutted and joined by a welded or soldered seam 16. The outer shell has a pair of inturned longitudinal abutting parallel flanges 15, the junction seam 40 of which is adapted to be filled with solder 15a to provide a smooth joint.

Each of the end discs 12 and 13 is offset outwardly at its central portion to form an annular boss 17, 18. The center of each boss 17, 18 is 45 apertured at 17a, 18a and spun inwardly to form a curved seat for the outwardly spun annular rim of the hub 14 (see Fig. 3). For strengthening and stiffening the end discs 12 and 13 and also to eliminate any sharp edges, the peripheral 50 sections thereof are curled over upon themselves

to form open beads 19 and 20, said beads lying in substantially the same plane as the bosses 17, 18, so that the spool will have a stable support on a horizontal surface. This construction also permits the spools to be readily stacked.

Shoulders 21 and 22 are formed on the discs 12 and 13 at the outer edges of the bosses 17 and 18, to provide suitable seats for the ends of the outer barrel 11, the grooves therebetween being filled up and smoothed by a fillet of solder 23. The bosses 17 and 18 are perforated with a plurality of circular apertures 24, and the barrel 11 is provided with a plurality of rows of spaced apertures 25, so that the silk thread or other material wound on the spool will be freely exposed to the action of the steam or other medium to which it is to be subjected.

It has been found in many cases that in drying the spooled thread after it has been steamed, the shrinkage of the thread will exert sufficient 20 compressive force to cause the outer shell or barrel to collapse inwardly unless properly reinforced. For this purpose, each of the end discs 12 and 13 is provided with a plurality of integral inwardly extending sheared concave nibs or lugs 25 26 struck up from the metal at the outer part of the raised bosses 17 and 18 adjacent the shoulders 21, 22 (see Figs. 2 and 3).

The nibs 26 comprise a plurality of shoulders 30 26a which are adapted to fit within the end edge wall of the barrel 11 at a plurality of spaced points, thus providing a strong reinforcement thereof. If desired, the central portion of the barrel 11 may also be reinforced. For this purpose, provision may be made of a circular transverse plate 27, provided with a central aperture 35 with an annular flange 28 for tightly fitting upon the tubular hub 14. The plate 27 has a rim slot 28a for accommodating the inturned flanges 15 of the barrel 11.

The plate 27 preferably has a peripheral flange 29 for engaging the interior surface of the outer barrel 11, said flange serving to hold said plate from twisting out of position. The plate 27 has a plurality of spaced apertures 30 to allow the 45 circulation of the steam through the interior of the spool.

While there has been disclosed in this specification one form in which the invention may be embodied, it is to be understood that this 50 form is shown for the purpose of illustration only, and that the invention is not to be limited to the specific disclosure, but may be modified and embodied in various other forms without departing from its spirit. In short, the invention 55

includes all the modifications and embodiments coming within the scope of the following claims.

Having thus fully described the invention, what is claimed as new and for which it is desired to secure Letters Patent is:

1. In a winding spool, a tubular outer barrel, a pair of apertured end plates having axially outwardly offset central bosses surrounding said apertures to form interior shoulders for receiving the opposite ends of said barrel, said plates having a plurality of spaced nibs projecting inwardly from the outer portions of said bosses adjacent said shoulders for reinforcing the edge of the interior wall of said barrel.
- 10 2. In a winding spool, a sheet metal shell having its longitudinal edges abutted and welded along a linear seam for forming a tubular spooling barrel, a pair of apertured end plates having axially outwardly offset central bosses surrounding said apertures to form interior shoulders for receiving the opposite ends of said barrel, said plates having a plurality of spaced nibs projecting inwardly from the outer portions of said bosses adjacent said shoulders for reinforcing the edge of the interior wall of said barrel.
- 20 3. In a winding spool, a tubular barrel, a pair of circular end plates having outwardly formed center bosses to form interior shoulders for receiving the opposite ends of said barrel, said bosses having central co-axial apertures, a tubular hub engaging in said apertures, said end plates having a plurality of spaced nibs struck inwardly from the body of said bosses adjacent said shoulders for supporting the interior wall of said barrel to prevent collapse thereof under the compressive forces of the thread on said spool while drying.
- 25 4. In a winding spool, a tubular barrel a pair

of circular end plates having outwardly formed center bosses to form interior shoulders for receiving the opposite ends of said barrel, said bosses having central co-axial apertures, a tubular hub engaging in said apertures, said end plates having a plurality of spaced nibs struck inwardly from the body of said bosses adjacent said shoulders for supporting the interior wall of said barrel to prevent collapse thereof under the compressive forces of the thread on said spool while drying, and a transverse plate on said hub for reinforcing the intermediate section of said barrel.

5 5. In a winding spool, a tubular barrel, a pair of circular end plates having outwardly formed center bosses to form interior shoulders for receiving the opposite ends of said barrel, said bosses having central aligned countersunk openings, a tubular member extending co-axially through said barrel and having its opposite ends spun outwardly upon the edges of said countersunk openings, said plates having a plurality of spaced nibs formed inwardly from the body of said bosses adjacent said shoulders for supporting the end edges of said barrel against collapse, and a transverse reinforcing circular plate within in said barrel for reinforcing it against collapse.

6. In a winding spool, a tubular outer barrel, a pair of end plates each having an axially outwardly offset central boss, annular shoulders being formed at the outer rims of said bosses to receive the ends of said barrel, said bosses having a plurality of spaced inwardly extending projections at their outer portions for holding the ends of said barrel against said shoulders to reinforce said barrel against inward compressive forces from the material wound on said spool.

FREDERICK R. REUTTER.
